DEAD END CONNECTOR

Edward S. Raila, Norwalk, and Robert O'Keefe, Stamford, Conn., assignors to Burndy Corporation, a corporation of New York

Application August 19, 1957, Serial No. 679,012

3 Claims. (Cl. 174—79)

This invention relates to connectors for anchoring the ends of cables to a supporting structure and more particularly it relates to dead end connectors for supporting a main cable in position while electrically and mechanically coupling a tap line to the main cable.

It is common in high power transmission lines to use an outer stranded cable conductor made of metal having high electrical conductivity, such as aluminum, over a re-enforcing core of steel. An example is the aluminum cable with steel re-enforcement commonly called ACSR.

In the past, anchorage for this type of transmission line has been provided by connectors having two concentric sleeves of different lengths, the outer sleeve attached to the aluminum conductor strands and the inner sleeve attached to the steel core. In one prior art dead end type of connector each sleeve terminated at the free end of the cable in a clevis and the pair of clevises were disposed one within the other. Oppositely positioned holes in each clevis were aligned to take an anchor pin which attached each cable member through its respective clevis to the supporting structure.

This type of prior art connector has many disadvantages; for example, it is important in the use of composite cables for transmission lines that the stress on each member of the cable occurs simultaneously to prevent an unbalanced strain. Each cable member, being provided with its attached clevis must be aligned with one another and therefore, a balanced stress is difficult to achieve.

Another type of prior art connector comprises a bent tube to which is brazed a clevis formed of a material having more advantageous structural characteristics than the material of the connector. One of the disadvantages of this type of connector is the prevention of the use of a standard clevis, since the clevis member is brazed to the bent tube connector. This brazing operation also adds to the cost of the fitting.

One of the objects of our invention, therefore, is to provide a one piece dead end connector suitable for the electrical and mechanical connection of a main line and tap line which may be attached to a supporting structure by means of the usual clevis.

Another object of my invention is to provide a one piece dead end connector which eliminates the need for multiple parts while allowing the use of an oxidizing inhibitor in one or both conductor receiving sections.

Further objects of our invention are to provide a one piece dead end connector which can be manufactured at a reduced cost due to the elimination of multiple part handling, which is labor saving during installation and in which identical connections are provided for attaching the cable members.

One of the features of our invention is the provision of a one piece dead end connector fitting for securing a cable to a support which comprises a main line cable receiving portion and a tap line conductor receiving portion, extending angularly from the main line portion. A neck portion having a changed cross-section connects the two line portions. The neck portion may comprise

2

a flattened bend in order to act as a stop for inhibitor which may be contained in the tubular line portion. The main line portion is upset or headed adjacent to the neck portion in order to form an integral collar to which 5 a clevis may be coupled for securing said fittings and cables to a support.

The above mentioned, and other features of our invention, will become more apparent by reference to the following description taken in conjunction with the accompanying drawings in which:

Fig. 1 is a view in elevation, partly in section, of our dead end connector into which cables have been inserted and the connector indented to the cable members;

Fig. 2 is a longitudinal plan view of the connector 15 shown in Fig. 1;

Fig. 3 is a view in elevation showing a pair of dead end connectors in accordance with the principles of our invention used with a jumper conductor; and

Fig. 4 is a view in elevation of a dead end connector 20 in accordance with the principles of our invention prior to the insertion of any cables or indentation operation.

Referring to Figs. 1 and 2 of the drawing a dead end connector in accordance with the principle of our invention is therein shown to comprise a one piece dead end type of connector 1 made of electrically conducting ductile metal, terminating at one end in a hollow tubular main line portion 2 adapted to receive a transmission line cable 3. The cable 3 may be the conventional high strength type of ACSR cable consisting of a steel core 30 and an aluminum sheath conductor member.

At the other end a hollow tubular tap or jumper line portion 4 extending at an angle to the main line portion 2 is adapted to receive a second or jumper conductor 5. A neck portion 6 integrally connects the main line and 35 tap line portions 2 and 4 respectively.

The main line portion 2 is upset or headed adjacent to the neck portion 6 to form a collar 7. A standard clevis 8 is positioned about the collar 7 and connected to a supporting structure (not shown) in a conventional manner by bolt 10 and nut 11. The main line and tap line tubular portion 2 and 4 receive the conductors 3 and 5 and are attached thereto, preferably by crimping and indentation as shown at 9a and 9b although other methods of attaching the connector to the conductor may be utilized.

45 A length of the tubular portion 2 may be tapered toward its free end, as shown in Fig. 1, by reducing its thickness. The tapered construction has a two-fold advantage. Firstly, the strain on the connector is redistributed so that the greatest strain is furthermore from the free end or mouth of the tubular portion, which is the weakest point as it is the point where the connector first takes the load. Secondly, the effect of cable vibration is reduced by gradually relieving the "notched effect." The tensile strength of the sheath conductor member is 50 gradually transferred to the tubular portion progressively from the mouth.

In many connections it is desirable to include an oxidation inhibiting compound within the connecting member. One such compound is "Penetrox" manufactured by the Burndy Corporation of Norwalk, Connecticut, and described in greater detail in the U.S. Patent No. 2,423,290 issued to W. F. Bonwitt. The dead end connector of our invention offers distinct advantages when such oxidation inhibitors are contained 55 within the connector. It should be noted that the main tubular portion is hollowed, but due to the bend and the reduced cross-section of the neck, a stop is formed preventing the inhibitor compound from flowing beyond the end of the main tubular portion.

70 The method of manufacturing the dead end connector of our invention is extremely simple and cheap,

and offers distinct advantages over the manufacturing methods of prior connectors of this type. A length of aluminum tubing is the initial starting material. The tubing is headed to form the collar 7 for holding the clevis 8. The aluminum tubing may then be flattened and bent at the flat to form the neck portion 6. This method of forming the neck 6 also produces a stop so that any inhibitor contained in the main tubular portion cannot flow out of the cable gripping section. Alternately, the neck portion 8 may be bent without flattening and if the bend is sufficient, the inner walls of the tube will meet and form a stop for the inhibitor. The finishing operations for the dead end connector includes chamfering and tapering the tubular portion and placing knurls to indicate where the connector should be crimped.

Referring to Fig. 3 of the drawing, there is therein shown a pair of dead end connectors 12 and 13 coupling a pair of main line conductors 14 and 15 through a jumper conductor 26. Each dead end connector 12 and 13 is similar to the dead end connector 1 of Fig. 1 and includes main line tubular portions 16 and 21, collars 19 and 24, integral necks 18 and 23, and jumper line portions 17 and 22 respectively. The clevises 20 and 25 supporting the connectors 12 and 13 about collars 19 and 24 may be coupled to a supporting structure, or in the alternative coupled to each other in such a manner as to form a jumper line.

Referring to Fig. 4 of the drawing, an uninstalled dead end connector in accordance with the principles of our invention is therein shown to comprise a main line tubular portion 27 and a tapline portion 28 integrally joined by a neck portion 29. The main line tubular portion 27 is headed to form a collar 30 for attachment of a supporting clevis not shown. Each of the tubular line portions 27 and 28 is knurled at a plurality of locations 33a and 33b to indicate where the installer should crimp the connector. Installation of the dead end connector of our invention is extremely simple. The oxidizing inhibitor is placed within the main line tubular portion 32 and may also be placed within the tap line tubular portion 31. The main conductor is then inserted in the main line tubular portion and a crimping tool crimps the connector to the conductor

at the point indicated by the knurling. In a similar manner the tap line may be coupled to the dead end connector.

While we have described above the principles of our invention in connection with specific apparatus, it is to be clearly understood that this description is made only by way of example and not as a limitation to the scope of our invention as set forth in the objects thereof and in the accompanying claims.

We claim:

1. A one piece fitting for securing a cable to a support formed of a malleable metal tube having a given diameter comprising a main line portion for electrically and mechanically connecting said cable, a tap line portion for electrically and mechanically connecting said fitting to a second cable, said tap line portion extending angularly from said main line portion, a neck portion having flattened cross-section connecting said main line portion and said tap line portion, the said neck, tap line and main line portions being formed integrally with each other, and a headed collar section having a diameter greater than said given diameter of said tube on said main line portion adjacent to said neck portion to provide for the attachment of a clevis.

2. The method of manufacturing a one piece dead end connector for securing a cable to a support comprising the steps of heading a tube composed of a highly conductive, malleable metal to form a collar, bending said tube adjacent to said collar, to dispose the ends of said tube in angular relation to each other and reducing the cross-section at said neck to avoid a hollow connection between said ends.

3. The method of manufacturing a one piece connector according to claim 2 which further includes flattening said tube adjacent to said collar prior to bending.
